CAKE DISPLAY PACKAGE

Helen G. Grant, Arden, N. C.

Application May 25, 1950, Serial No. 164,169

1 Claim. (Cl. 206—45.33)

1

This invention relates to a container for holding articles having a tacky surface and more particularly to a container for holding iced cakes and the like.

Heretofore in the art, much difficulty has been encountered in devising a container for articles having a tacky surface which would sufficiently protect the tacky surface from damage when wrapped, and yet be of such a construction that it could be easily and readily assembled, and could properly display the article contained therein. Previous attempts to solve this problem have resulted in containers which are of complicated structures and consequently difficult and time-consuming to assemble. Most of these attempts have manifested limited success because the complicated structures have made it necessary to have the container itself become the feature of attractiveness due to the fact that the article contained therein could not be properly displayed. This situation is exemplified by Patent No. 1,941,538 to T. C. Costello.

It is an object of this invention to provide a container for holding articles having a tacky surface that will afford a better protection to the tacky surface when wrapped than has heretofore been available.

It is another object of this invention to provide a container for this purpose that is of a simple construction to allow a more easily and readily assemblage than has heretofore been available.

It is another object of this invention to provide a display container for cakes and the like that will afford visual access to a maximum area of the article contained therein.

Other objects and advantages of the present invention will become apparent from a study of the following specification when considered in conjunction with the drawings, in which:

Figure 1 is a perspective view of an assembled container constructed according to the principles of the present invention showing a cake on display within the container and under a transparent wrapper constituting a part of the container.

Figure 2 is a view in vertical section taken along the line 2—2 of Figure 1;

Figure 3 is a plan view of the blank which forms the base member of the container; and

Figure 4 is a plan view of the blank which forms a cross member of the container.

Figure 1 shows the assembled container holding an iced cake 10. The cake 10 is encased in a transparent wrapping 11 and rests on a sup-

2

port member 12, the upstanding end portions of which are connected by a cross member 13.

The support member 12 as shown in Figure 3 consists of a rectangular piece of paper board, cardboard, or other suitable material. This board is provided with scoring at 14 and 15 to divide the board into a large central portion 16 and smaller end portions 17 and 18. Each end portion has a slot 19 cut therein. The support member 12 is adapted to being made into a U-shaped member by folding the end portions upwardly along scored lines 14 and 15. It is in this shape that it is used with the cake 10 resting on the central portion 16.

15 The cross member 13 as shown in Figure 4 consists of a strip of tough resilient paper board or cardboard. This strip may be cut from the same material as support member 12, except that the cutting procedure is different. Support member 12 must be cut with the grain of the paper board to facilitate the bending along the scored lines 14 and 15, whereas cross member 13 must be cut against the grain of the paper board to prevent cracking or sharp bending at any point along its length so that when member 13 is in position it will tend to assume the shape of a bow or arch due to its resilience. The length of cross member 13 is equal to or slightly greater than the blank from which support member 12 is cut. The length of member 13 depends on the degree of arch required in the strip 13 above the support 12. This height is dependent upon the size of the article to be packaged and is variable. The width of the cross member 13 is substantially equal to the width of slots 19 in the ends of the support member 12. Each end of cross member 13 passes through slots 19 from the outside to the inside of support member 12 thus raising a resilient arch support across the top of support member 12.

40 When pressure is exerted downwardly against the arched member 13 the pressure brings the ends of arched cross member 13 in contact with the bottom 16 of the support member 12, causing the resilient arched cross member 13 to release contact with end portions 17 and 18 of support 12. When downward pressure is removed, the resilient arched cross member 13 springs upward and away from the top of the cake 10, thus releasing the pressure of the ends of cross member 13 against the base 16 and causing a return of pressure to the end portions 17 and 18.

45 A transparent wrapper is then drawn across the package in such a manner as to encase the

package firmly but not tightly. This firm pressure of the transparent wrapper exerts sufficient pressure on the arched cross member 13 to hold the end portions 17 and 18 in vertical position. The transparent wrapper must be neither too loose nor too tight but must allow for the play of pressure downward on arched cross member 13 against the end portions 17 and 18 of support 12, so that the resilience of 13 is unimpaired and will always respond in rebound from pressure.

To assemble the various parts of the container and to wrap a cake effectively, the procedure is as follows. The support member 12 is first bent at scored lines 14 and 15 into a U-shape. Then the iced cake 10 mounted on a paper board base is put into support member 12 by placing it on central portion 16. The cake base has the same dimensions as the cake 10 so that its edge will act as a guide during the icing of the cake 10. It is important to note that the end portions 17 and 18 stand at a height above the level of the iced cake 10. The cross member 13 is then arched sufficiently to insert its respective ends into slots 19 in end portions 17 and 18 of support member 12. The central portion of cross member 13 prevents the wrapping 11 from contacting the cake 10 and damaging its icing. Also the co-action of the support member 12 and cross member 13 permits a dead air space between the wrapping 11 and the cake 10. This serves to keep the icing moist.

The resilience of the material used in the cross member 13 is of such a nature that pressure exerted from the outside across the top of the strip causes the strip to bend without breaking and rebound immediately once the pressure is removed. Suitable materials for cross member 13 are railroad board, card stock or the like. In addition, the strip may serve a dual purpose and may be imprinted with trade names, cake and icing specifications, or other printing necessary to proper labeling of the package. In this manner all other forms of labeling may be entirely eliminated.

If desired, each end portion of the support member 12 may be provided with two slots. However, if two slots are used, the end portion of the strip must pass through the first slot from the inside to the outside and through the second from the outside to the inside in order to have the edge of the end portion of the cross member resting on the central portion of the support member. In this instance, the cross member affords no support to the external edge of the end portion of the support member. If the end portion of the cross member is presented to the slots oppositely, it will result in not supporting the internal edge of the end portion of the cross member.

What has been described heretofore is a specific embodiment of this invention. Other and further embodiments, as well as various modifications obvious from this description to one skilled in the art, are within the contemplation and spirit of this invention. For example, it may be desirable to provide a cake support member having upstanding side portions at each side thereof in addition to the upstanding end portions. This may be particularly suitable if the support could be economically manufactured from transparent material. In using such an embodiment it would then be desirable to use two cross members, one engaging slots in the end portions and the other engaging slots in the side portions.

What is claimed is:

A package comprising an article having a tacky surface, a protective and display container therefor consisting essentially of a U-shaped support having a central portion and two upstanding end portions each having a slot near the top edge, a resilient, non-scored cardboard cross member cut lengthwise against the grain to permit arching but resist sharp bending or cracking, said cross member having a slightly greater length than the overall length of the U-shaped support when in flattened condition and extending over the top of the support in the form of an arch with each end passing downwardly through the slot in each upstanding end portion from the outside to the inside and resting on the bottom of the support, a transparent wrapping enclosing the support and cross member, and said cross member constituting a protective element to prevent the wrapping from contacting the top tacky surface of the article while the pressure exerted by the wrapping on the arch of the cross member causes spreading of the upstanding end portions away from the side tacky surfaces of the article.
